UNITED STATES PATENT OFFICE.

CHARLES M. KRUGER, OF ST. LOUIS, MISSOURI.

CARRYING FRAME.

Application filed March 23, 1927. Serial No. 177,507.

This invention relates to carrying frames, in which bottles of oil or the like may be conveniently carried from one place to another.

An object of the invention is to provide an improved frame constructed and arranged to support familiar types of oil containing bottles having spouts for the discharge of the oil, and means in connection with the frame for covering the open ends of the various spouts, and a handle structure supporting said means.

Another object of the invention is to provide an improved frame for supporting and carrying and protecting oil containing bottles possessing the advantages herein disclosed, reference being made to the drawing, in which

Fig. 1 is a plan view of my improved frame.

Fig. 2 is a side elevation with the parts in section.

Fig. 3 is an end elevation.

Fig. 4 is a sectional view on an enlarged scale on the line 4—4 of Fig. 3.

In the embodiment of the invention shown, the bottom of the frame is in the form of a pan. This bottom is preferably made of sheet metal and includes a bottom wall 1 pressed to provide upraised circular elevations 2, for the respective bottles, and a surrounding upturned flange 3. This pan will catch and prevent the oil from dripping from the frame. As shown, the bottles are seated upon the respective elevations 2.

The upper portion of the frame comprises a plate 4 shaped or formed to provide openings 5 in vertical alignment with the bottom elevations 2 and through which the bottles 6 are passed into and withdrawn from the frame. Each of the openings 5 is surrounded by a downwardly extended flange 7, serving to strengthen the structure. The plate 4 is also surrounded by a depending marginal flange 8. The flanges 8 at the sides are connected with the flanges 3 of the bottom wall by plates 9 and at the ends by plates 10 pressed to form channels through which the downwardly extended ends of the handle supporting bar 11 extend. The ends of the

handle supporting bar 11 are secured to the flange 3 of the bottom by rivets 12 and to the flange 8 by rivets 13. This handle supporting bar extends longitudinally throughout the length of the frame and has a down-

wardly bent central portion 14 through which the ends of the bail 15 extend. The bail 15 is held in connection with the central portion 14 of the bar 11 by nuts 16. A coiled wire handle 17 is preferably secured to this bail.

The spout 18 of the bottles 6 have beveled discharge ends and, when the bottles are placed in the frame, the bevels of the spouts are toward the axis of the frame which is toward the longitudinal portion of the bar 11. Two pairs of arms 19 are pivoted to the bar 11 adjacent to the ends of the downwardly bent intermediate portion 14 of said bar. Each bar of these arms supports a plate 20 having its outer and end edges bent to provide flanges 21.

The parts are in such relationship that, when a row of bottles is in the frame at either side of the bar 11 with the bevels of the spout 18 toward the axis of the frame, the corresponding plate 21 will seat closely against the beveled ends of said spouts, as clearly shown in Fig. 3, and thus prevent dust and particles and other foreign matter from entering the bottles and fouling the oil. When it is desired to remove one or more of the bottles, this may be done simply by tilting the upper end of the bottle outwardly away from the plate 19 and withdrawing the bottle from the frame.

In the construction shown, the frame is designed and adapted to support two rows of bottles, each row comprising four bottles, thus rendering the frame easily portable when containing a considerable quantity of oil. The frame may be manufactured and sold at comparatively low cost. It is strong and durable and easily carried. The structure and relationship of the parts may be varied equivalently without departure from the principle of the invention.

I do not restrict myself unessentially, but what I claim and desire to secure by Letters Patent is:—

1. A frame comprising a bottom having depressed portions to contain oil and flat elevated portions to support bottles, an upper frame part having openings in vertical alignment with the respective elevated portions of the bottom, a bar extending longitudinally above the frame and having its ends attached to said bottom and to said upper frame part, two pairs of arms pivoted

to said bar, and a plate attached to each pair of arms and arranged to engage against the beveled ends of bottle spouts.

2. A frame comprising a bottom having flat elevated portions to support bottles, an upper frame part having openings in vertical alinement with the respective elevated portions of the bottom, a bar extending longitudinally above the frame and having its ends attached to said bottom and to said upper frame part, two pairs of arms pivoted to said bar, a plate attached to each pair of arms and arranged to engage against the beveled ends of bottle spouts above the plane of said bar, and a handle attached to said bar and extending upwardly between said plates for carrying the frame and preventing said plates from swinging to opposite sides of said bar.

20 3. A frame of the character described comprising a metallic bottom pan to receive and contain oil, a metallic frame above said pan for holding bottles on said pan, elements rigidly connecting said pan and said frame, a bar extending longitudinally above said frame below the plane of the upper ends of bottles for which the device is intended and having its ends extending downwardly and attached to said frame and to said pan, a pair of arms pivoted to said bar, and a plate attached to said arms for engaging rigidly against the ends of bottles for which the device is intended.

35 4. A frame of the character described comprising a sheet metal bottom having flat elevated portions, a sheet metal upper frame having openings in vertical alinement with said elevated portions, a bar extending longitudinally above said frame and having its ends extended downwardly and attached to said frame and said bottom, a downwardly

bent intermediate part on said bar, two pairs of arms pivoted to said bar at the ends of said downwardly bent portion, and a plate attached to each pair of arms.

45 5. A frame of the character described comprising a sheet metal bottom having flat elevated portions, a sheet metal upper frame having openings in vertical alinement with said elevated portions, a bar extending longitudinally above said frame and having its ends extended downwardly and attached to said frame and said bottom, a downwardly bent intermediate part on said bar, two pairs of arms pivoted to said bar at the ends 55 of said downwardly bent portion, a plate attached to each pair of arms, and a handle bail attached to said downwardly bent portion of said bar.

60 6. A frame of the character described comprising a sheet metal bottom having depressed portions to contain oil and flat elevated portions above said depressed portions to support bottles above the oil in said depressed portions, an upper frame having 65 openings in vertical alinement with said elevated portions to receive and hold bottles seated on said elevated portions, and a handle device in connection with said frame.

70 7. A frame of the character described comprising a sheet metal bottom having elevated portions to support bottles and depressed portions below the elevated portions to receive oil dripping or flowing from the bottles, a sheet metal upper frame having 75 openings in vertical alinement with said elevated portions to receive and retain bottles on said elevated portions out of the oil in the depressed portions of said bottom, and a handle device in connection with said frame.

CHARLES M. KRUGER.
